UNITED STATES PATENT OFFICE.

GEORGE F. SIMONDS, OF FITCHBURG, MASSACHUSETTS.

INSERTIBLE-TOOTH SAW.

SPECIFICATION forming part of Letters Patent No. 326,685, dated September 22, 1885.

Application filed July 7, 1885. (No model.)

To all whom it may concern:

Be it known that I, GEO. F. SIMONDS, of Fitchburg, in the county of Worcester and State of Massachusetts, have invented certain 5 Improvements in Inserted-Tooth Saws; and I hereby declare the following to be a full, clear, and exact description of the same, reference being had to the accompanying drawings, making part of this specification, in which—
10 Figure 1 is a side elevation of a portion of a saw-plate provided with the improved inserted tooth. Fig. 2 is a side elevation of a section of a saw-plate with the tooth and gullet removed. Fig. 3 is a perspective view of 15 the removable point. Fig. 4 is a perspective view of the removable gullet. Fig. 5 is a cross-sectional view on the line $\alpha\alpha$ of Fig. 1.

My invention relates to that class of inserted-tooth saws wherein the point is secured 20 to the saw-plate by means of a removable gullet sprung into the recess in the plate, and has for its object to so strengthen the removable gullet that it may be made narrower than heretofore with safety, and thereby enable me to increase the size of the pocket or 25 space within the gullet for carrying the dust, and at the same time broaden the face of the gullet and tooth, so as to make proper clearance in the cut or kerf.

30 In the respects named my present invention is an improvement on the invention described and claimed in an application filed by me April 22, 1885, Serial No. 163,032.

In order that those skilled in the art may 35 make and use my invention, I will proceed to describe the manner in which I have carried it out.

In the said drawings, A is a section of a saw-plate provided with the recess B, for the 40 reception of the removable gullet and tooth, the said recess being cut in the arcs of two circles of different radii, but struck from about the same center. The removable gullet C has its rear edge grooved at a' to fit over the beveled edge a of the recess B, and its body b is made of a thickness greater than the thickness of the saw-plate, while each exterior rear edge is beveled off, as seen at d d , so that the lowest lines of the beveled edges are 45 incident with the plane of the saw-plate when the gullet abuts against the plate. The in-

serted point D is provided with a swaged cutting-edge, e , as is usual in such cases, and has its body formed with a thickness of metal greater than the thickness of the saw-plate, 55 but equal to the thickness of the body b of the removable gullet C. The rear exterior edges of the point D are beveled, as seen at i i , so that the lowest line of the bevels are coincident with the planes or faces of the saw-plate 60 when the point is set. The rear edge of the point is provided with a groove, l , to fit over the beveled edge l' of the recess B. The base of the point when inserted and in place rests against the projection n , cut in the saw-plate 65 and connecting the two arcs in which rest the bodies of the removable gullet and tooth.

By means of the construction of tooth and gullet described and illustrated I am not only 70 enabled to manufacture them at a less cost than heretofore, but the weight of metal obtained by thickening the body of the tooth and the body of the gullet enables me to increase the interior curve of the gullet, and thereby increase the size of the dust-carrying 75 pocket, and yet maintain the requisite strength necessary to the successful working of the saw, every fraction of increase in the size of the dust-carrying pocket being of the greatest value in the perfection of work performed by a circular saw. 80

I am aware that heretofore the working-faces of removable gullets and removable teeth for circular saws have been swaged to a dimension greater than the thickness of the saw-plate; but in such cases the strength of the parts has not been so increased as to have 85 them narrower, and thereby increase the size of the gullet or pocket materially, as is the case with my invention.

Having thus described my invention, what I claim as new, and desire to secure by Letters Patent, is—

1. The removable gullet C, having its body thicker than the saw-plate, in combination 95 with a recessed saw plate and tooth, substantially as described.

2. The removable gullet C, having its body thicker than the saw-plate and its rear exterior edges beveled, as shown at d d , in combination with a recessed plate and a tooth, for 100 the purpose set forth.

3. The removable tooth D, having its body thicker than the saw-plate, as specified, in combination with a holding device and a recessed plate, as described.

5 4. The removable tooth D, having its body thicker than the saw-plate and its rear exterior edges beveled, as shown at *i i*, in combination with a holding device and a recessed saw-plate, substantially as set forth.

GEO. F. SIMONDS.
